(57) **CLAIM**

The ornamental design for a slicer for fruits and vegetables, as shown and described.

DESCRIPTION

FIG. 1 is a side perspective view of the slicer for fruits and vegetables of the present invention;

FIG. 2 is a bottom perspective view of the slicer for fruits and vegetables of the present invention;

FIG. 3 is a side view of the slicer for fruits and vegetables of the present invention;

FIG. 4 is a front view of the slicer for fruits and vegetables of the present invention;

FIG. 5 is a top perspective view of the slicer for fruits and vegetables of the present invention, with the slicer in an open position;

FIG. 6 is a bottom perspective view of the slicer for fruits and vegetables of the present invention, with the slicer in an open position; and,

FIG. 7 is a side view of the slicer for fruits and vegetables of the present invention similar to FIG. 3, but with the slicer in an open position.
